(57) **CLAIM**

The ornamental design for the adapter for the camping stove hanging kit, as shown and described.

DESCRIPTION

FIG. 1 is a top perspective view of the adapter for a camping stove hanging kit, showing our new design;

FIG. 2 is a bottom perspective view thereof;

FIG. 3 is a front view thereof;

FIG. 4 is a back view thereof;

FIG. 5 is a side view thereof;

FIG. 6 is another side view thereof;

FIG. 7 is a top view thereof;

FIG. 8 is a bottom view thereof; and,

FIG. 9 is a perspective view of the adapter in a condition of use.

The broken lines in the drawings depict portions of the adapter for a camping stove hanging kit and environmental structure of the camping stove hanging kit that form no part of the claimed design.
